EJECTOR FORK

Filed Aug. 7, 1931

FIG. 1

FIG. 2

FIG. 3

INVENTOR.
THOMAS S. HUTCHISON

BY *Albert C. Bell*
ATTORNEY.

UNITED STATES PATENT OFFICE

THOMAS S. HUTCHISON, OF CHICAGO, ILLINOIS

EJECTOR FORK

Application filed August 7, 1931. Serial No. 555,670.

My invention relates to an improved construction of ejector fork by which articles of many kinds may be handled by the fork and removed from the fork by the ejector mechanism as described.

My invention is an improvement on constructions heretofore proposed for accomplishing the purpose referred to, and is characterized particularly by making the ejector mechanism of wire bent so that a single piece of wire constitutes the ejecting member, the thumb or finger hold for operating the ejector, the retaining member in the handle of the fork for holding the ejecting member in assembled relation and limiting its outward or ejecting movement and also engaging a spring in the handle for holding the ejecting mechanism in its retracted position, without the addition of any parts whatever to the bent wire. By my improved construction, the bent wire ejecting mechanism is completely formed as a separate unit, in such a manner that without deformation of any kind, it may be assembled on the fork and require no forming or adjusting after assembly, the mounting of the shank of the fork in its handle, serving to retain the parts in their assembled relation. In this manner, I provide a cheap and simple construction for the purpose referred to, which at the same time is most effective in operation.

My invention will best be understood by reference to the accompanying drawings showing a preferred embodiment thereof, in which

Fig. 1 shows my construction in perspective view in assembled relation, with the handle of the fork shown in longitudinal, sectional view to illustrate the relation of the parts in the handle,

Fig. 2 is a plan view of the form of fork member I prefer to use, and

Figure 3 shows in a view similar to Fig. 1, the ejector mechanism before it is assembled on the fork member.

Similar numerals refer to similar parts throughout the several views.

As shown in Fig. 1, my improved fork construction consists of a fork member 10, made preferably of metal wire bent to the form in-

dicated, so that the mid portion of the wire after it is bent, forms the shank end 11 of the fork member, the sides of the shank portion being spaced and in substantially parallel relation to receive between them a retracting 55 spring 12 and the hook shaped end 13 of the ejecting mechanism. The wire thus bent constitutes the shank, a loop with closed ends, or in effect, produces a slotted shank construction. The ends of the bent wire forming the fork member 10, are spaced from each other and in substantially parallel relation as indicated at 14, 14 to form the tines of the fork member, the ends of the tines being 60 preferably provided with small teeth 15, 15 tending to hold on the fork, articles that may 65 be handled by it.

The ejector mechanism 16 consists of a metal wire bent at one end to form a flat loop 17 loosely surrounding the tines 14, 14 from 70 which loop the body portion of the ejector mechanism extends closely adjacent the fork member 10, to a position near the handle 18, where the wire of the ejector mechanism is bent to form a ring 19 substantially parallel 75 with the end of the handle and preferably somewhat larger than the end of the handle. From the ring portion 19, the wire of the ejector mechanism is bent to form the hook portion 13 which is substantially parallel 80 with the shank portion 11 of the fork member, the hook 13 in its assembled condition, extending between the side members of the shank portion 11 and interlocking with the shank portion, so that the end of the wire is 85 substantially in the plane of the ring portion 19. In this manner, the hook portion 13 serves as a guide for the ejector mechanism since the members of the hook portion are upon opposite sides of the body portion of 90 the fork member, and the bend 13b of the hook portion 13 limits outward movement of the ejector mechanism by engaging the bends in the fork member where the spaced portions of 95 the shank of the fork member, merge into the body portion of said member. The spring 12 is hooked at its ends around the bend 13b and around the butt end of the shank 11 of the fork, preferably in a notch 20 formed in the shank portion to hold the spring in place. 100

The handle 18 is provided with a bore 21 which is a snug sliding fit on the shank portion 11 of the fork member, and the end of the handle 18 adjacent the ring portion 19, is preferably provided with a metal ferrule 22 against which the radial portion or portions of the ring portion 19 may rest, when the ejector mechanism is in its fully retracted position under the action of the spring 12. This it will be noted, retains the hook portion 13 of the ejector mechanism in guiding relation with the body portion of the fork member 10.

The construction of the fork member 10 and of the ejector mechanism 16 is more clearly shown in Figs. 2 and 3, where these parts are illustrated in their disassembled condition. From the construction of the parts above described, it will be observed that the ejector mechanism may be made completely as a separate unit and from a single piece of metal wire, as illustrated in Fig. 3, and that this mechanism may be assembled on the fork member shown in Fig. 2, by inserting the tines 14, 14 through the ring 19 and then through the loop 17, and then sliding the ejecting mechanism towards the shank of the fork member until the free side 13a of the hook portion 13 clears the end 11a of the space between the side members of the shank 11 of the fork member, which permits the free side 13a of the hook portion, to pass through the space in the shank portion, so that the spring 12 may be hooked at one end around the bend 13b of the hook portion 13, and at its other end around the end of the shank portion 11 in the notch 20, so that the spring is contained in the space between the side members of the shank portion 11. The ejecting mechanism 16 is then moved towards the points of the tines with the side members of the hook portion 13 on opposite sides of the body portion 10 of the fork member, and the shank portion 11 is then inserted in the bore 21 in the handle 18, the parts having sufficient frictional engagement to hold the fork in its completely assembled condition resulting from the operations described. From the construction described, it will appear that the bend 13b of the hook portion 13 engages the bends in the shank 11 at 11a, when the ejector mechanism is moved to its ejecting position, the proportions of the parts being such that for this relation, the flat loop 17 is still on the tines 14, 14 of the fork, adjacent their ends. The ring 19 permits the operation of the ejector mechanism in a convenient manner either by the thumb or finger of the hand holding the fork, regardless of the position in which the fork may be, when it is grasped by the operator.

Where the fork member 10 is made as described, the body portion between the shank 11 and the tines 14, 14, consists preferably of parallel portions of the wire of which the

fork member is made, which portions are securely held together in any convenient manner, for example by spot welding, soldering or brazing. It will be understood that this construction of the fork member is illustrative and that any equivalent construction may be used.

From the above it will appear that the entire fork structure, including the ejector mechanism, consists of but three parts in addition to the handle, namely the fork member, the ejector member, and the spring; that each of these parts is of cheap construction; that each part may be made in finished form as a unit before the assembly of the structure; and that the parts may be easily and quickly assembled, without the use of tools or fastening devices of any kind; all of which combines to reduce the manufacturing cost of the complete fork. At the same time, the construction may readily be made as substantial as desired and in any size desired, so that it may effectively handle any and all articles susceptible of being handled by a fork, with the advantage that the articles handled may be removed from the fork by the ejector mechanism, by the same hand that is used to hold the fork. A fork construction of this kind is particularly useful in many ways for household purposes, particularly where it is desired to handle hot articles.

While I have shown my invention in the particular embodiment above described, it will be understood that I do not limit myself to this exact construction as I may employ equivalents known to the art at the time of the filing of this application without departing from the scope of the appended claims.

What I claim is:

1. In an ejector fork, the combination of a fork member comprising a metal wire bent into a shank loop, a body portion, and spaced tines, an ejector member comprising a metal wire bent into a flat loop loosely surrounding said tines, a body portion extending along the fork member, a ring surrounding the fork member; and a flat hook extending through said shank loop, a retracting spring connecting said hook and the butt end of said shank loop and contained in said shank loop, and a handle on and surrounding said shank loop with its end adjacent said ring.

2. In an ejector fork, the combination of a fork member having spaced tines, a body portion, and a slotted shank, an ejector member comprising a wire shaped into a loop surrounding said tines, a body portion extending along the fork member, a ring surrounding said fork member, and a hook extending through said slotted shank, a retracting spring connected with said hook, and a handle on said slotted shank.

In witness whereof, I hereunto subscribe my name this 3rd day of August, A. D. 1931.

THOMAS S. HUTCHISON.
